CLAIM

The ornamental design for an IV pack, as shown and described.

DESCRIPTION

FIG. 1 is a left, front isometric view from above of the IV pack with the top partially opened.

FIG. 2 is a right, back isometric view from above of the IV pack of FIG. 1.

FIG. 3 is a right, front isometric view from below of the unopened IV pack; and,

FIG. 4 is right, back isometric view from above of the unopened IV pack of FIG. 3.

The broken line shown on the top edge of the claimed design in the drawings is a line of stitching and forms a part of the claimed design.
